UNITED STATES PATENT OFFICE.

GEORGE BASTIAN, OF MARION, OHIO.

REED-STONING MACHINE.

Application filed November 14, 1923. Serial No. 674,777.

This invention relates to a machine designed particularly for stoning or honing the reeds which are used in connection with the weaving of fabrics, the present invention being an improvement over the machine disclosed in my prior Patent No. 1,441,392, issued Jan. 9, 1923.

The present invention has for its object to simplify the construction and mounting of the movable parts of the machine, to provide more compact and more reliable driving connections, and to enable the movement of the various parts to be more conveniently controlled.

15 A further object of the invention is to provide a supporting head for the stone which is more compact, has fewer parts and is less liable to get out of order in the operation of the machine.

20 A further object is to provide an adjustable counter-balanced and yielding support for the stone whereby the pressure of the stone upon the work can be accurately regulated and whereby the stone is protected 25 against injury by engagement with obstructions or irregularities on the work.

A further object is to provide means whereby the work may be adjusted transversely as well as longitudinally with respect to the stone, whereby the effective 30 stroke of the stone on the work may be varied.

A further object is to provide means for automatically shifting the work longitudinally during the operation of the stoning device and in connection with said shifting device to provide means whereby the work 35 may be shifted manually during the operation of the machine to facilitate repeated 40 stoning operations on portions of the work which may be rougher than others.

A further object is to simplify the means for lifting the stone carrying element at the end of the stroke.

45 Other objects will be apparent from the following description and accompanying drawings.

The following description and accompanying drawings set forth in detail certain 50 means embodying the invention, the disclosed means, however, constituting but one of the various mechanical forms in which the principle of the invention may be employed.

55 Reference should be had to the accom-

panying drawings forming a part of this specification in which Fig. 1 is a top plan view of the machine with end portions of the work carrying member broken away; Fig. 2 is a front elevation of the machine 60 with end portions of the work carrying member broken away; Fig. 3 is a central transverse vertical section through the frame of the machine and the work supporting bed, the reciprocating head in this 65 view being shown in side elevation; Fig. 4 is a vertical section through the head on line 4-4 of Fig. 5; Fig. 5 is a section on line 5-5 of Fig. 4 looking down; Fig. 6 is a detailed view of the pawl guard shifting lever. 70

Referring to the accompanying drawings, the entire mechanism is mounted upon a rectangular box-like stand 1 which has a ledge 2 along the front side thereof upon which the fixed support 3 for the work 75 carrying bed is mounted. At the top thereof the stand 1 has fixed thereto a pair of guides 4 between which the sliding head which carries the stone is mounted and, at the rear thereof, the stand 1 is provided 80 with a stand 5 which supports the motor for driving the mechanism.

Extending longitudinally along the top of the support 3 for the sliding bed there is an undercut guide rib 6 which is slidably engaged by the base portion 7 of the work supporting bed. Extending longitudinally along the bottom of the base portion 7 of the work supporting bed there is a rack 8 which is engaged by a pinion 9 fixed 90 to a shaft 10 which extends transversely through the support 3, the support 3 being provided with a suitable slot 11 to receive the pinion 9. The work carrying portion 12 of the bed rests upon the top of the base portion 7 thereof and is provided with a projection 13 on its underside which extends into a wide longitudinal slot 14 in the base member 7. The projection 13 is provided with a transverse threaded opening which 100 receives a screw 15 which extends through the outer side portion of the base 7 and has a reduced end portion 16 to which is fixed a hand wheel 17. Between the inner end of the reduced portion 16 and the hub of 105 the hand wheel 17 there is a thrust plate 18 which is fixed to the base portion 7 of the bed and serves to hold the screw 15 against longitudinal movement. The work W is supported at the top of the upper portion 12 110

of the bed and is held against lateral movement by means of ribs 19 extending along the edges of the portion 12.

By rotating the hand wheel 17 the upper work carrying portion 12 of the bed may be shifted laterally so that the work may be accurately adjusted with respect to the reciprocating stone. The bed may also be so adjusted that the outer edge portion of the reed frame will not be engaged by the stone on its forward stroke. This adjustment also permits reed frames of various widths to be properly positioned with respect to the reciprocating head.

15 The entire mechanism is operated by a motor 20 mounted upon the rear platform 5 through a worm 21 and worm gear 21^a within a gear housing 22 mounted on the platform 5. Connected to the worm gear 21^a is a vertical shaft 23 which is journaled at its lower end in the casing 22 and adjacent its upper end in a bearing bracket 24 attached to the rear side of the supporting stand 1. At its upper end above the top surface of the stand 1 the shaft 23 carries a wheel 25 to which is eccentrically connected the rear end of a connecting rod 26 which is connected by a vertical pivot at its forward end to the sliding head 27. The head 27 is provided on opposite sides thereof with undercut horizontal guide ribs which engage with undercut horizontal grooves in the guide members 4. It will thus be seen that when the motor 20 is in operation the head 27 will be constantly reciprocated.

During the reciprocation of the head the work supporting bed is shifted longitudinally in one direction or the other with a step by step movement so that the work is progressively acted upon from one end to the other by the stone. The step by step movement is imparted to the work carrying bed by the movement of the head and the mechanism by means of which this movement is effected will now be described. The shaft 10 is extended inwardly into the supporting stand 1 and is journaled in bosses 30 and 31 which project inwardly from the front and rear walls of the stand, respectively. Between the bosses 30 and 31 beveled gears 32 and 33 are rotatably mounted on the shaft 10. At one side of the shaft 10 and at right angles thereto there is mounted a horizontal spindle 34 which has its inner end adjacent the shaft 10 and midway between the gears 32 and 33. At its inner end the spindle 34 has loosely mounted thereon a beveled gear 35 which meshes with the two beveled gears 32 and 33 on the shaft 10. Immediately behind the gear 35 on the spindle 34 there is a ratchet wheel 36 which rotates with the gear 35. Pivotied to the hub of the ratchet wheel 36 is an upwardly extending arm 37 which has adjacent the upper end thereof a longitudinal

slot 38 which receives a pin 39 carried by a bracket 40 projecting from the underside of the slide 27. The arm 37 has pivoted thereto a pawl 41 which is preferably spring pressed toward the ratchet wheel 36 into engagement with the teeth thereof. The teeth of the ratchet wheel 36 are so disposed that the pawl 41 will engage therewith during the rearward movement of the head 27 and the pawl 41 will ride over the teeth during the forward movement of the head. As the head 27 is reciprocated the ratchet wheel 36 will thus be given an intermittent rotary movement in one direction.

The intermittent movement of the bed is effected through the ratchet wheel 36 and in order to vary the rate of movement of the bed for different operations, I have provided means for varying the amount of angular movement which is imparted to the ratchet wheel 36 upon each reciprocation of the head 27. To this end the segmental guard plate 43 is fixed to the spindle 34 at the rear of the ratchet wheel 36 and has its outer portion projecting slightly beyond the periphery of the ratchet wheel into the path of movement of the pawl 41. To the outer end of the spindle 34 outside the stand 1 there is fixed an adjusting lever 44 which lies adjacent the wall of the stand 1 and is provided with an arcuate slot 45 adapted to receive a bolt 46 projecting from the wall of the stand and adapted to clamp the lever in various adjusted positions. By adjusting the lever 44 the segmental guard 43 may be adjusted to prevent engagement of the pawl 41 with the ratchet wheel 36 during any desired portion of its rearward movement, thus the extent of angular movement of the ratchet wheel 36 for each stroke of the head can be accurately adjusted.

To provide a driving connection between the intermittently actuated ratchet wheel 36 and the shaft 10 which is geared to the bed, a sliding clutch member 47 splined to the shaft 10 is interposed between the gears 32 and 33 and is adapted to be moved into engagement with either of two clutch elements 48 and 49, one on the gear 32 and the other on the gear 33, by means of a suitable shifting lever 50. By means of the clutch element 47 either of the gears 32 or 33 may be clutched to the shaft 10 whereby the shaft 10 will be given an intermittent rotary movement corresponding to the intermittent rotary movement of the ratchet wheel 36 and in either direction depending upon which one of the gears 32 or 33 is engaged by the clutch element 47. After the bed has traveled far enough in one direction for the work to have moved its full length beneath the head, the clutch 47 will be shifted to reverse direction of movement of the bed and by adjusting the guard member 43, the rate of longitudinal movement of the

work may be varied. Where some portions of the work are rougher than others, it may be desirable to operate repeatedly upon these portions. The reversing gear 5 permits the direction of movement of the work to be reversed at any time so that the operations may be repeated upon any desired portion of the work. In finishing the work it is often desirable to move the stone a few 10 times across widely separated parts of the work and in order to provide for rapid shifting of the work the shaft 10 has been extended and provided with a squared end 51 adapted to be engaged by a hand crank so 15 that by shifting the clutch member 47 to neutral position the movement of the work bed may be controlled by hand.

The slide 27 has an upright front end portion 52 which projects above the body thereon 20 and serves as a support for the movable portions of the head. The front portion 52 of the slide has a reentrant vertical channel 53 formed in the front face thereof which forms a chamber for certain of the movable parts of the head. At the front edges of the channel 53 there are vertical undercut guide ribs 54 and 55 which serve as guides for a slide 56 which has an undercut groove 57 formed to receive the guide ribs 54 and 55. 30 The slide 56 at the top and bottom corners thereof has forwardly projecting lugs 58 and 59 and on its front face has outwardly inclined guide ribs 60 and 61 which extend vertically and serve as guides for a vertically movable tool carrier support 62 which has an undercut groove 63 in its rear face to receive the guide ribs 60 and 61.

Secured to the top of the channel portion 53 at the front of the head is a cap 64 which is provided with a screw threaded opening which is engaged by a vertically disposed tubular screw 65 provided with a hand wheel 66 at its upper end. Slidably mounted in the channel 53 is a block 67 which has an upwardly projecting stem 68 slidable in the tubular screw 65. Interposed between the block 67 and the lower end of the tubular screw 65, there is a coiled spring 69 encircling the stem 68. The spring 69 serves to yieldingly press the block 67 in a downward direction and the screw 65 serves to adjust the tension of the spring 69. The block 67 has a recess 70 at its lower end which is open to the bottom and to the front of the block. Within this recess there is mounted a pawl 71 which pivots about a horizontal pin 72. The pawl 71 has an arm 73 extending upwardly above the pivot and an abutment 74 on the inner side thereof below the pivot which is adapted to engage with the rear wall of the recess 70 to limit the swinging movement of the pawl. A coiled spring 75 is interposed between the rear wall of the recess 70 and the arm 73 and serves to yieldingly press the abutment 74 against the wall

of the recess 70 thereby holding the pawl 71 in substantially vertical position. The lower end of the pawl 71 engages the upper end of a vertical pin 76 which is slidably mounted in the bottom member at the lower end of the channel 53. Beneath the bottom of the head the pin 76 has a flange 77 formed thereon which is normally held in engagement with the lower end of a housing member 78 secured to the bottom of the head by means of a coil spring 79 surrounding the pin 76 and interposed between the flange 77 and the bottom of the head. The lower end of the pin 76 is tapered and rests upon a cam track 80 which has an upwardly inclined portion 81 which serves at one portion of the stroke of the head to elevate the pin 76 and through the pin 76 to lift the movable portions of the head so as to lift the stone out of engagement with the work. 85 The cam track 80 is preferably adjustable longitudinally to permit the length of the working stroke to be varied. It will be seen that the slide 67 is normally supported by the pin 76, the tension of the spring 69 not 90 being sufficient to overbalance the spring 75 so that while the pin is traveling over the forward straight portion of the track 80, the parts will be held in the position shown in Fig. 4. When, however, the pin 76 engages 95 with the inclined portion 81 of the trackway there will be an additional upward pressure upon the lower end of the pawl 71 slightly in front of the pivot 72 which will cause the lower end of the pawl to swing forwardly 100 compressing the spring 75. As the pawl 71 moves forwardly, it will engage with a tooth of a vertically disposed ratchet 82 secured upon the rear face of the slide 56 so that the slide 56 and parts carried thereby 105 will be elevated with the pin 76. At the upper end of the slide 56 there are a pair of upstanding arms 83 to which the forks of a forked lever 84 are pivotally connected. The forked lever 84 straddles the adjusting 110 screw 65 and is pivoted to a bracket 85 fixed to the upper end of the front portion 52 of the slide by means of a horizontal pivot 86 which passes through the lever 84 immediately at the rear of the forked portion thereof. A counterweight 87 is slidably mounted upon the rearwardly extending portion of the lever 84 and is adapted to be secured in adjusted position thereon by means of a suitable set screw 88. The counterweight 87 115 may be adjusted to as nearly counterbalance the weight of the movable portions of the head as desired. The tool carrier support 62 has lugs 90 projecting laterally from the side edges thereof adjacent the center and interposed substantially midway between the outwardly projecting lugs 58 and 59 of the slide 56. Coil springs 91 are interposed between the lugs 90 of the tool carrier support 120 and the upper lugs 58 of the slide and coil 125

springs 92 are interposed between the lugs 90 and the lower lugs 59 of the slide 56. The springs 91 and 92 provide a yielding support for the tool carrier holder 62 and permit movements of the tool holder support independently of the slide.

The tool carrier support 62 has a downwardly inclined forwardly projecting skirt portion 93 which has side flanges projecting upwardly therefrom and forming between them a channel for receiving the tool holder. Pivoted on a horizontal cross pin 95 extending between the flanges 94 there is a tool holder 96 which has an upwardly extending arm 97 above the pivot between which and the upper portion of the support 62 is interposed a compression spring 98 which exerts outward pressure on the arm 97. Below the pivot 95 the tool holder 96 has parallel spaced arms 99 which are normally held by the spring 98 in engagement with an abutment 100 which extends across the lower end of the skirt 93.

The stone 101 is held between a pair of clamp members 102 and 103 which are secured together by means of clamping screws 104, the clamp members 102 and 103 having edge flanges 105 and 106 engaging the inner and outer sides of the arms 99 of the holder so that the tool is slidably mounted between the arms 99. The upper flanges 105 are cut away toward the lower end portion thereof to provide shoulders 107. Secured to the arms 99 are screws 108 behind which the shoulders 107 of the clamp engage whereby the downward movement of the clamping members is limited. A rubber buffer 109 is interposed between the stone clamping members and the tool holder 96 which serves to normally hold the stone carrying clamp in engagement with the screws 108.

As the head is reciprocated, the stone 101 is yieldingly held in engagement with the work. Upon rearward movement of the head, the stone 101 is so supported that any obstruction or irregularity of the work will cause the stone to swing upwardly, the spring 98 permitting the holder 96 to swing about its pivot. Upon outward movement of the head, the stone will be cushioned by the buffer 109 and also by the coiled springs 91 and 92 through which the tool carrier support is yieldingly supported so that any obstruction engaged by the stone which might otherwise damage or break the stone will cause the stone to be shifted upwardly, first compressing the buffer 109, then shifting the support 62 bodily. The pressure exerted by the stone upon the work may be very accurately regulated by adjusting the counterweight 87 which determines the weight imposed upon the stone. In the normal operation of the machine the stone will bear against the work with a pressure determined

by the setting of the counterweight and in addition to this the stone is provided with yielding connections with the counterweighted portions of the head to enable the stone to have the quick yielding movements necessary to prevent injury to the stone by engagement with irregularities or obstructions.

Having described my invention, I claim—

1. In a machine of the character described, a supporting stand, a head mounted to slide upon said stand, a counterbalanced tool support slidably mounted on the head, and a rigid tool yieldingly mounted on the support.

2. In a machine of the character described, a supporting structure, a laterally movable head carried by the supporting structure, a tool support mounted to slide up and down on the head, and a counterbalance adjustably connected to the support whereby the pressure with which the tool is held to the work may be varied.

3. In a machine of the character described, a supporting stand, a head slidably mounted on the stand, a tool support mounted on the head for movement by gravity toward the work, a tool carried by the support and yieldably connected thereto, and means for counterbalancing said support.

4. In a machine of the character described, a supporting structure, a movable head carried by the supporting structure, a tool support mounted to slide up and down on the head, a lever connected at one end thereof to the tool support and fulcrumed on said head, and a counterweight adjustably mounted on said lever.

5. In a machine of the character described, a supporting structure, a reciprocating head carried by the supporting structure, a tool slidably and pivotally connected to said head, and yielding means for normally holding the tool in a predetermined position with respect to the head and for resisting sliding and pivotal movements of said tool with respect to the head.

6. In a machine of the character described, a supporting structure, a movable head carried by the supporting structure, a tool support mounted on the head and movable by gravity toward the work, a tool movably connected to said support and adapted to be pressed against the work by said support, a spring interposed between said tool and support, and a counterweight connected to said support, said counterweight being adjustable to vary the pressure on the tool.

7. In a machine of the character described, a supporting structure, a movable head carried by the supporting structure, a tool support carried by the head and movable thereon by gravity toward the work, a work engaging tool, means for yieldably con-

necting said tool to said support, and means operable at one portion of the movement of the head for lifting the tool support.

8. In a machine of the character described, 5 a supporting structure, a head mounted on the supporting structure for movement in a fixed path, a member mounted for vertical movement on the head, a cam track upon which said member travels, a tool support mounted for free movement by gravity on said head, a tool yieldingly mounted on said support, and means for automatically connecting said member to the tool support to lift the same upon upward movement of 15 said member.

9. In a machine of the character described, a supporting structure, a reciprocating head carried by the supporting structure, a tool support mounted for movement by gravity 20 on said head, a tool carrier slidably mounted on said support for vertical movement with respect thereto, and pivoted to swing about a horizontal axis, and springs for yieldingly resisting the sliding and pivotal movements 25 of said tool carrier.

10. In a machine of the character described, a supporting structure, a movable head carried by the supporting structure, a member slidably vertically on the head, 30 forwardly projecting upper and lower lugs on said member, a tool carrying member slidably mounted on said first mentioned member, said tool carrying member having a lug interposed between the upper and lower lugs of the first mentioned member, and compression springs interposed between 35 the lug of the tool carrying member and the upper and lower lugs of the first mentioned member.

40 11. In a machine of the character described, a supporting structure, a movable head carried by the supporting structure, a member slidably vertically on the head, an adjustable counterbalance for said member, 45 a tool carrying member slidably mounted on said first mentioned member, and upper and lower oppositely acting compression springs interposed between said members for yieldingly supporting said tool carrying member on said first mentioned member.

50 12. In a machine of the character described, a supporting stand, a work support, a head slidably mounted on the stand and movable over the work support, a tool support mounted on the head for free movement thereon toward the work by gravity, a work engaging tool, and means for yieldably connecting said tool to said tool support.

60 13. In a machine of the character described, a supporting structure, a work support, a head carried by the supporting struc-

ture and movable over the work support, a tool support mounted on the head for free movement toward the work by gravity, a 65 work engaging tool, means for yieldably connecting said tool to said tool support, and means operating during the movement of the head for lifting the work support and tool from the work.

70 14. In a machine of the character described, a supporting structure, a longitudinally movably work support, a tool carrying head adapted to reciprocate on said structure transversely of the work support, means 75 operated by the head during its movement in one direction for imparting a longitudinal movement to the work support, and means for varying the extent of such longitudinal movement so imparted to the work 80 support.

15. In a machine of the character described, a supporting structure, a longitudinally movable work support, means for adjusting the work laterally on said support, 85 and a tool carrying head adapted to be reciprocated on said structure transversely of the work support.

16. In a machine of the character described, a supporting structure, a longitudinally movable work support, a tool carrying head mounted for reciprocating movement on said structure transversely of the work support, means for reciprocating the head, 90 means operated by the head in its reciprocating movement for moving said work support step by step in either direction, and means 95 for shifting said work support manually.

17. In a machine of the character described, a supporting structure, a reciprocating head carried by the supporting structure, a tool carrier pivotally connected to said head, a spring yieldingly resisting pivotal movement of said tool carrier, a tool 100 slidably mounted on said tool carrier, and means for yieldingly resisting sliding movement of the tool.

18. In a machine of the character described, a supporting structure, a movable head carried by the supporting structure, 110 a tool support slidable thereon, a slide interposed between the head and tool support, a ratchet carried by the tool support, a pawl carried by the slide, a spring normally holding said pawl out of engagement with the ratchet, a second slide engaging said pawl, 115 and a cam track upon which said slide travels, said cam track having a portion thereof adapted to impart a movement to said second slide to engage said pawl with the ratchet and to shift said tool support.

In testimony whereof, I hereunto affix my signature.

GEORGE BASTIAN.
